UNITED STATES PATENT OFFICE

164,271

ROOFING SHINGLE

Herbert Abraham, New York, N. Y., assignor to
The Ruberoid Co., Bound Brook, N. J., a cor-
poration of New Jersey

Application November 22, 1949, Serial No. 6,192

Term of patent 14 years

(Cl. D68—1)

To all whom it may concern:

Be it known that I, Herbert Abraham, a citizen of the United States, residing at city, county, and State of New York, have invented a new, original, and ornamental Design for a Roofing Shingle, of which the following is a specification, reference being had to the accompanying drawing, forming part thereof.

Fig. 1 is a plan view of a roofing shingle showing my new design, and

Fig. 2 is a butt or lower edge view thereof.

I claim:

The ornamental design for a roofing shingle, substantially as shown.

HERBERT ABRAHAM.
